TOY

Floyd D. James, San Antonio, Tex.

Application November 5, 1934, Serial No. 751,652

3 Claims. (Cl. 46—50)

This invention relates to toy gliders or aeroplanes and a catapult therefor and has for the primary object the provision of a device which may be propelled with great force and is capable of maintaining flight for a maximum distance and in a desired course and which will be simple, durable, and efficient and which may be manufactured and sold at a low cost.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a toy constructed in accordance with my invention.

Figure 2 is a top plan view illustrating the 20 glider or aeroplane.

Figure 3 is an end view illustrating the same.

Figure 4 is a detail sectional view taken on the line 4—4 of Figure 1.

Figure 5 is a side view illustrating a catapult.

Figure 6 is a top plan view illustrating the 25 same.

Figure 7 is a side view illustrating a modified form of connecting the elastic element to the handle of the catapult.

Figure 8 is a top plan view illustrating a modified form of my invention.

Referring in detail to the drawing, the glider or aeroplane consists of a fuselage 1 in the form of an elongated stock having its forward end rounded, as shown at 2, and its rear end notched, as at 3, to be engaged by an elastic element 4 of a catapult 5. The stock 1 is provided with a longitudinally extending groove or channel 6 opening outwardly through the upper edge thereof to provide flexible parallel portions 7 between which is received a rudder or keel 8 constructed of any material suitable for the purpose and is adapted to maintain the fuselage on an even keel while in flight. The stock 1 is cut away to form spaced recesses or seats 9 in which are mounted forward and rearward planes or wings 10 and 11. The plane or wing 10 forms a main support for the fuselage while in flight and the wing or plane 11 acts as a stabilizer. The inner walls of the seats 9 are arcuately curved while the end walls are formed on converging planes so that when the planes or wings are inserted in the seats they are disposed at a desired inclination and also frictionally contact with the walls of the recesses and are maintained against accidental

displacement. The wings or planes are constructed of any material suitable for the purpose and as shown in Figure 2 are arranged transversely of the fuselage. The rudder or keel 8 is capable of adjustment endwise of the stock or fuselage and if desired the parallel portions 7 of the stock may be provided with bolts or similar fasteners 12 which when adjusted will bring about a gripping of the parallel portions 7 on the keel or rudder to hold the latter against accidental displacement.

Mounted in the channel 6 forwardly of the plane or wing 10 and adjacent the front end 2 is a weight 13 acting to balance the fuselage while in flight and is capable of adjustment endwise of the stock. The weight may be of any desired shape and constructed of any material suitable for the purpose. Adjacent the rear end of the stock 1 are notches 14 to be engaged by the thumb and finger of a hand of a person while in the act of shooting the device into the air by the catapult 5. The latter consists of a handle 15, one edge of which is notched, as shown at 16, to form a guide and seat for the stock 1, this being clearly illustrated in Figure 1. Said 20 notched end of the handle 15 is also provided with slots 17 through which the elastic element 4 is passed. The elastic element in this form is of endless construction. If desired, the elastic element may be constructed in strip formation 30 with the ends thereof laced through spaced slots 18, as shown in Figure 7. The slots are angularly related relative to one another to define therebetween tapered tongues 19, the faces of which cause a binding effect upon the elastic element 35 and prevent accidental detachment of said element from the handle.

In operation, the device is positioned on the catapult 5, as shown in Figure 1, the operator gripping the handle 15 in one hand and the rear end of the stock with the thumb and finger of the other hand and by exerting a pull on the stock in a rearward direction a desired tension will be placed upon the elastic element for propelling the glider or aeroplane through the air with considerable force when the stock is released by the finger and thumb of the hand of a person.

Either end of the keel 8 may be flexed laterally of the stock in either direction for the purpose of changing or varying the direction of flight of the device. By reference to Figure 2 it will be seen that the ends of the keel may be moved out of the groove 6 of the stock so that the end portions of the keel may be flexed to lie against either side of the stock. The cutaway portions in the stock 55

which form the seats 9 will permit the end portions of the keel to be moved out of the groove 6 and flexed against either side of the stock.

Having described the invention, I claim:

- 5 1. A toy aeroplane comprising an elongated stock having spaced cutaway portions to form seats and provided with a channel opening outwardly through its upper edge and intersecting the seats, wings mounted in said seats, a semirigid keel extending into the channel and capable of manual flexion, and means for securing the keel to the stock intermediate the ends of said keel, either end of said keel being capable of flexion so as to lie either in the channel or outwardly of the channel upon either side of the stock.
- 10 2. A toy aeroplane comprising an elongated stock having a channel opening outwardly through its upper edge and extending substantially the full length of said stock, an elongated keel mounted in said channel and projecting outwardly therefrom and extending substantially the full length thereof, a balancing weight mounted
- 15

in said channel forwardly of the keel, and wings mounted to the stock and arranged transversely thereof and in a plane below the keel and located adjacent the ends of the latter.

- 5 3. A toy aeroplane comprising an elongated stock having a channel opening outwardly through its upper edge and extending substantially the full length of said stock, an elongated keel mounted in said channel and projecting outwardly therefrom and extending substantially the full length thereof, a balancing weight mounted in said channel forwardly of the keel, said stock having recesses forming seats each provided with an arcuately curved inner wall and angularly related end walls, and semirigid wings capable of manual flexion transversely thereof and mounted in said seats with opposite edges thereof contacting the angularly related end walls of said seats whereby the transverse curvature of the wings and pitch thereof may be varied by adjusting said edges along said last-named walls.
